UNITED STATES PATENT OFFICE.

SIDNEY JAMES THOMAS LONG, OF AUCKLAND, NEW ZEALAND.

WATER HEATER.

Application filed September 15, 1920. Serial No. 410,438.

To all whom it may concern:

Be it known that SIDNEY JAMES THOMAS LONG, citizen of the Dominion of New Zealand, residing at Auckland, New Zealand, has 5 invented certain new and useful Improvements in Water Heaters, of which the following is a specification.

This invention relates to water heaters of that class wherein water jackets or spaces 10 enclose a heat or combustion chamber, and water is caused to circulate around baffle plates fitted in chambers exposed exteriorly to heated gases, for the purpose of providing a large heating surface and of presenting 15 the water to the latter in a thin body, in order to ensure rapid heating.

The object of the present invention is to provide an improved construction of heater wherein water can be rapidly and economically 20 heated to the required degree of temperature, the construction being such that the apparatus can be readily taken apart for inspection, cleaning and repair purposes.

According to the invention the heater is 25 formed with separate sides, back and front, each of which contains a vertical water space.

The invention will be further described with reference to the accompanying drawings, in which:—

Figure 1 is a side elevation of the heater, and

Figure 2 a plan view of same with the cover removed.

Figure 3 is a front sectional elevation, with the cover and base removed, while

Figure 4 is a sectional elevation of the back and front.

Figures 5 and 6 are a front sectional elevation (with cover removed), and a sectional plan respectively, of a modified construction.

Referring to the drawings, for the purposes of illustration, 1 and 2 represent sides 45 of the heater and 3 and 4 the back and front thereof. Each of the sides 1 and 2, the back 3 and the front 4, is formed separately and contains a vertical water space 5.

The sides 1 and 2, back 3 and front 4 are 50 secured together to provide an enclosed heat or combustion chamber 6 by couplings 9 which pass across the interior corners of said meeting sides, back and front.

Detachable clips 7 which engage beads or 55 projections 8 on the exterior corners of the

meeting sides 1 and 2, back 3 and front 4, also serve to hold the latter securely together, (Figure 2).

From said sides 1 and 2, back 3 and front 4, tubes 10 (Figures 2, 3, and 4) project 60 horizontally into the chamber 6, said tubes being closed at their outer ends, and projecting almost right across said chamber 6. The tubes 10 are also preferably tapered as illustrated in Figure 2.

Baffle plates 11 secured to the outer walls of the sides 1 and 2, back 3 and front 4 extend almost to the outer ends of said tubes 10 and divide the latter into upper and lower compartments, said plates 11 being kept centrally within the tubes 10 by studs or spacers 11^a.

The tubes 10 are flattened and in communication with the water spaces 5 of the sides 1 and 2, back 3 and front 4.

The baffle plates 11 extend the full width of the tubes 10, so that communication between the upper and lower compartments of said tubes is provided only at the outer ends of the latter.

The projection of the tubes 10 from the sides 1 and 2, back 3 and front 4 is arranged as shown in Figure 3, so that a zig-zag or tortuous passage as indicated by the arrows (Figure 3) is provided upwards in the chamber 6 for the heated gases, which must necessarily pass between said tubes 10, so that the latter provide considerable heating area.

The sides 1 and 2, back 3 and front 4 rest on a base 12 provided with a channel 13 as shown in Fig. 5, which collects and disposes of the effects of condensation.

A cover 14^a provided with an uptake 15 is fitted to the sides 1 and 2, back 3 and front 4.

Heat is generated by any suitable means, such as a gas burner 16 located beneath the lower end of the device. The heated gases pass upwards between the sides 1 and 2, back 3 and front 4, and circulate through tortuous passage below, between and over the tubes 10, and finally escape through the uptake or vent 15.

From the inlet pipe 17 water enters the top of the space 5 of the side 1 and passes downwards through said side 1 and over and under the baffle plates 11 in the tubes 10 in communication therewith, to the lower coupling 9 leading into the bottom of the water space 5 of the back 3. Said water

then rises in the back 3 and passes under and over the baffle plate 11 in the tube 10 open to the water space of said back 3, and enters the top of the water space of the side 2, by way of the upper coupling 9. From the top of said side 2, the water passes downwards in the water space thereof, and over and under the plates 11 in the tubes 10 open thereto to the lower coupling 9, opposite the first mentioned lower coupling into the front 4 and then upwards in the water space 5 thereof, under and over the plate 11 in the tube 10 in communication therewith, and finally leaves the heater 15 through the outlet pipe 18 from the top of the front 4.

By having the inlet 17 and outlet 18 both at the top of the heater, the latter is always kept full of water and emptying is prevented. Also the whole of the water must pass through the tubes 10. There is no direct communication between the water spaces 5 of the side 1 and the front 4, the coupling 9^a shown in Figure 2 not providing communication between said spaces, but being merely a blank or provided only as a stay.

Where the heater is situated in the basement of a building and a substantial construction is necessary to withstand the pressure of water, the construction can be as shown in Figures 5 and 6, with the sides 1 and 2, back 3 and front 4 of stronger material than that used in the former construction 35 and bolted together by corner pieces 20.

Instead of employing flattened tubes 10, horizontal rows of tubes 21 each containing a baffle plate 11 as before are employed, only this construction the baffle plates 11 comprise 40 a series of fingers extending from plates 22 secured to the outer walls of the sides 1 and 2, back 3 and front 4 so that water can only pass from the upper or lower portion of a water space 5 to the lower or upper portion 45 thereof, by way of the tubes 21.

The tubes 21 are passed through the inner walls of the sides 1 and 2, back 3 and front 4 or plates attached thereto and are secured by back nuts 24.

50 The passage of water through the last described construction is similar to that which occurs in the first described construction.

In the latter construction, the heated gases pass upwards between the series of rows of

tubes 21, which cross each other as shown 55 in Figure 6.

What I do claim and desired to obtain by Letters Patent of the United States of America is:—

1. A water heater having independent 60 sides made up of spaced plates to provide a water space, means engaging the exterior plate of adjacent sides and thruout the longitudinal edges thereof to secure said sides together to form a rectangular heater, the inner wall of each side having tubes extending therefrom in open communication with the water space of that side, the tubes being of the full width of the side at their connection with the inner wall thereof and 70 tapering from this width toward their free ends, the respective tubes projecting from the respective sides in succession and being themselves spaced apart vertically of the heater, and means for heating arranged below the lowermost tube, whereby the tubes form complete baffles against the vertical movement of the heat products.

2. A water heater having independent 80 sides made up of spaced plates to provide a water space, means engaging the exterior plate of adjacent sides and thruout the longitudinal edges thereof to secure said sides together to form a rectangular heater, 85 the inner wall of each side having tubes extending therefrom in open communication with the water space of that side, the tubes being of the full width of the side at their connection with the inner wall thereof and tapering from this width toward their free 90 ends, the respective tubes projecting from the respective sides in succession and being themselves spaced apart vertically of the heater, a baffle plate arranged in each tube and connected to the outer wall of said side 95 and of the full width of the tube and side, the baffle plate extending within the tube and terminating short of the free end of the tube, and means for heating arranged below the lowermost tube, whereby the tubes 100 form complete baffles against the vertical movement of the heat products.

In testimony whereof I affix my signature in presence of two witnesses.

SIDNEY JAMES THOMAS LONG.
